[57] CLAIM

The ornamental design for a basket or similar article, as
shown and described.

DESCRIPTION

FIG. 1 is a perspective view of a basket showing my
new design,

FIG. 2 is another perspective view thereof,

FIG. 3 is a front elevational view thereof,

FIG. 4 is a rear elevational view thereof,

FIG. 5 is a top plan view thereof,

FIG. 6 is a bottom plan view thereof,

FIG. 7 is a right side elevational view thereof,

FIG. 8 is a left side elevational,

FIGS. 9, 10, and 11 are perspective views of alternative
embodiments of the design.

The tabletop and background woodwork in FIGS. 2-8
are no part of the claimed design.

FIG.1

FIG. 2

FIG. 3

FIG. 4

FIG. 5

FIG. 6

FIG. 7
